BY

James Sheely & Co., ATTORNEYS.

UNITED STATES PATENT OFFICE.

GEORGE FRANKLIN VAN METER, OF INDIANAPOLIS, INDIANA.

AUTOMATIC CONTROLLER FOR AIR-BRAKE EMERGENCY-VALVES.

1,303,743.

Specification of Letters Patent. Patented May 13, 1919.

Application filed October 19, 1918. Serial No. 258,802.

To all whom it may concern:

Be it known that I, GEORGE F. VAN METER, a citizen of the United States, residing at Indianapolis, in the county of Marion and 5 State of Indiana, have invented new and useful Improvements in Automatic Controllers for Air-Brake Emergency-Valves, of which the following is a specification.

This invention relates to a novel device 10 for automatically controlling the air brake emergency valve installed on railway trains.

The prime object of the invention is to provide simple, durable, economical and efficient means that will effectually operate an 15 emergency valve, and by so doing will automatically stop the train that is equipped with the air brake system, when the wheels of an engine, coal tender or car leave the track caused by an open switch, spreading 20 of the railroad rails, a broken railroad rail, or for other reasons any part of the train should be derailed. This automatic controller will bring the train to a sudden stop before the parts of the train that have left 25 the rail will be turned over or serve to cause the rest of the train being turned over or derailed, thereby causing injury and death to passengers and railroad employees, as well as creating much serious damage to railroad 30 property.

Another object of the invention is to provide a novel automatic controlling device, connected to the emergency valve on a railway train equipped with the usual air brake 35 system, which device is so connected to the trucks of a car, tender, or locomotive, that when the wheels thereof are derailed a member of the device will immediately and automatically contact with the track rail thereby 40 causing the device to open the emergency valve connected to the air brake system, apply the brakes and bring the train to a sudden stop.

The foregoing and such other objects as 45 may appear from the ensuing description are attained by the construction, combination, location and arrangement of the parts hereinafter more fully described, illustrated in the accompanying drawings, and particu- 50 larly pointed out in the claims appended hereto, it being understood that slight changes in the form, proportions and minor details of the construction may be resorted to without departing from the spirit or 55 sacrificing any of the advantages of the invention.

In the accompanying drawings which form a part of this specification, it will be seen that:

Figure 1, is side elevation partly in section, showing the novel controlling device embodying my invention as being connected to the trucks of a railway car. 60

Fig. 2, is a side elevation of the device, showing parts of the mechanism by dotted 65 lines inclosed within a casing carried by the trucks of a car, and

Fig. 3, is a view showing in detail the several parts of the device disconnected from each other and from the truck of the rail- 70 way car.

Similar numerals of reference are em- 75 ployed to designate corresponding parts throughout the several figures of the drawings.

In carrying out my invention the accom- 80 panying drawings of which illustrate the preferred construction, it will be understood that the parts of the device constituting my improved automatic controller are made of any suitable material, preferably of iron, and that there is to be four for each car and two for the locomotive of a railway train. 75

Having reference to Fig. 1, of the draw- 85 ings it will be seen that the numeral 1, designates the frame of a railway car truck, 2 the floor portion of the car, 3, an emergency valve of any suitable construction which is normally closed and connected by a depend- 90 ing branch pipe 4, to the train air pipe 5, 90 of the usual and well known air brake systems, and fixedly secured to the frame 1, in any suitable manner, is a casing 6, into which is fitted within a vertical guide-way 7, 95 formed therein, the upper portion 8 of a 95 plunger 9, provided with a reduced lower end portion 10, to which is fixedly se- 100 cured by the bolts 11, a depending extension 12 carrying at its lower end a cylindrical member or roller 13 secured across said end portion by any suitable means, and project- 105 ing beyond either side thereof, said member being adapted to contact with the top of the track rail 14, in the manner hereinafter described. Over the upper portion of the 105 said plunger and casing is fitted a head or cap 15, which is secured by a nut 16, carried at the upper end of the plunger. Project- 110 ing from one side of the casing 6, and in- 110 tegral therewith, is an extension 17, to the inner face to which is pivoted at 18, an S-shaped or obtuse angle lever 19, provided at

its lower end with a roller 20 adapted to normally rest within a recess or slot 21, formed in the upper portion of the plunger, and at its upper end with an opening for 5 the reception of a pin 22, for pivotally connecting thereto one end of a link 23, the other end being pivotally connected at 24 to the short vertical arm of a bell-crank or right-angle lever 25, which latter is pivoted 10 to the said extension 17, by a pin 26, the longer horizontal arm of the lever 25 extending through a slot formed in the cover for the extension and pivotally connected at its outer end to the lower end of an adjustable connecting rod, the upper end of said rod being connected to an arm 27, secured to the emergency valve and adapted to suitably operate said valve, said connecting rod, consisting of two rods, 28, 28, each being 15 screw threaded at one end thereof and adapted to receive a turnbuckle 29, by which the length of rod is suitably regulated and adjusted.

It will be readily perceived that the lower-25 most portion of the slot or recess in the plunger is formed with a gradual rounded surface 30, thereby permitting the roller 20, carried by the lever 19 to easily ride out of the recess when the plunger is caused to slide 30 upward by contact with the track rail when the wheels of the truck are caused from any reason to be derailed, and by the movement of said roller out of the path of the plunger a rocking motion is imparted to the 35 lever 19, thus causing the upper portion thereof to impart a forward movement to the link 23, and the vertical arm of the lever 25, thereby forcing the horizontal arm of the latter upward and through the medium 40 of the connecting rod and arm 27, causing the valve to move to open position, thus venting the air brake train line and properly and promptly applying the brake.

It will be understood that the cylindrical 45 or roller member carried at the lowermost end of the plunger is suspended only slightly above the track rail, hence when any of the wheels of the train equipped with my device leave the rail, said wheel will drop a sufficient distance to bring said member immediately into contact with the rail, thereby causing an upward sliding movement to the plunger which movement imparts motion to the other operating parts in the manner 55 hereinbefore referred to, and automatically operates the emergency valve, which operation will release the air in the train pipe 5, and the brakes will be quickly applied in the well known manner and make a sudden or 60 "emergency stop," and much loss of life and destruction of property may thereby be averted.

It will be readily obvious that my improved automatic controlling device may be 65 easily adjusted to operate in connection with

any known construction of emergency valve without materially changing any of the parts of the device.

It will be perceived that the lever 19 pivoted within the casing is provided at each side of its pivoted center with a coiled spring 19^a, one end of each spring resting in contact with said lever and the other end of the spring resting in contact with the casing, whereby the proper engagement of the roller 70 end portion of the lever with the recessed portion of the plunger 9 is insured, and the reduced end portion 10 of the plunger is provided with a vertical slot therethrough for suitably adjusting the depending extension 12 on said plunger, through the medium of the securing bolts 11, while said extension 12 is provided with a horizontal slot 12^a therethrough, through which slot is fitted the adjusting bolts and nuts 12^b for moving 80 the contact roller or cylinder member 13 to the right or left as may be desired.

Having thus described my invention, what I claim and desire to secure by Letters-Patent is:—

1. An automatic controller for air-brake emergency valves comprising the combination of a train-pipe, a branch pipe, an emergency valve connected to said branch-pipe, an arm connected to said valve, a car truck, 90 a casing mounted on said truck, a slideable plunger mounted within the casing provided with a recess portion and a cylindrical member secured to its lower end, a rocking lever pivoted within the casing provided with a roller at its lower end adapted to be seated within said recessed portion, said rocking lever imparting movement to an adjustable rod connected to the emergency valve for 95 opening the said valve.

2. An automatic controller for air-brake emergency valves comprising, in combination with the truck of a car, a fluid-pressure supply pipe, an emergency valve connected to said pipe, a casing mounted upon the 110 truck, a slideable plunger mounted in guideways within the casing having a reduced lower end portion carrying a depending portion secured to said reduced portion carrying a cylinder member at its lower end, and a 115 recess formed in the upper portion of the plunger within the casing, a rocking lever pivoted within the casing having a roller at its lower end normally seated in said recess—said rocking lever being adapted to 120 impart movement to an adjustable rod connected to the emergency valve for operating the same.

3. An automatic controller for air-brake emergency valves comprising, in combination with the truck of a car, a fluid-pressure supply pipe, an emergency valve connected to said pipe, a casing mounted upon the truck, a slideable plunger mounted within the casing provided with a recessed portion 125 130

- in the casing and a cylindrical cross member secured to its lower end positioned adjacent to a rail of a railway, a rocking lever pivoted within the casing having a roller at its 5 lower end adapted to be seated within said recessed portion of the plunger, and means connected to said rocker lever and to an adjustable rod connected to the emergency valve for operating said valve.
- 10 4. A device of the character described comprising, in combination with the truck of a car, a fluid-pressure supply pipe, an emergency valve connected to said pipe, a casing mounted upon the truck provided 15 with vertical guide-ways, a slideable plunger mounted within said guide-ways in the casing, said plunger having a recessed portion within the casing, and a cylindrical cross member secured to its lower end adapted to 20 be held adjacent to a rail of a railway, a rocking lever pivoted within the casing provided with a roller at its lower end resting normally within said recessed portion, and means connected to the upper portion of the 25 lever and to the lower end of an adjustable connecting rod, which latter is connected to the emergency valve for operating the same.
5. A device of the character described comprising, in combination with the truck of a car, a fluid pressure supply pipe, an 30 emergency valve connected to said pipe, a casing mounted upon the truck, a slideable plunger mounted within the casing having a recessed portion therein, and a cylindrical 35 cross member secured at its lower end, a rocking lever pivoted within the casing provided with a roller at its lower end adapted to be seated within said recessed portion, a link within the casing connected to the upper portion of the lever, a right angle lever 40 pivoted within the casing having a short vertical arm connected to said link and a longer horizontal arm extending outside of the casing, and an adjustable rod connected to the outer end of said horizontal arm and to the 45 emergency valve for operating the said valve.

In testimony whereof I have hereunto set my hand in presence of two subscribing witnesses.

GEORGE FRANKLIN VAN METER.
